DEHYDRATOR ATTACHMENT FOR TANKS

Lynn G. Lindsay, St. Paul, Minn.

Application February 26, 1944, Serial No. 524,147

2 Claims. (Cl. 312—31.1)

1

It is an object of this invention to provide a novel dehydrator attachment for guarding against the harmful effects of condensation of moisture in tanks under freezing conditions, the device being particularly although not exclusively adapted for use in connection with the fuel tanks of motor vehicles and airplanes.

A further object is to provide an attachment of this class having a container at least a portion of which is transparent and wherein the dehydrating material is associated with a coloring agent subject to change of color upon adsorption of a predetermined proportion of moisture so that by mere inspection it can be determined when the dehydrating material should be replaced.

Other objects will appear and be more fully pointed out in the accompanying specification and claims.

Clogging of fuel conduits and mechanism such as fuel injectors, pumps and carburetors during the operation of motors under freezing conditions is frequently caused by condensation and freezing of the moisture which enters the fuel tanks with the air necessarily admitted to replace the fuel as it is used. By the use of the present invention I obviate this difficulty by drying the air continuously in the tank.

Referring to the accompanying drawing:

Figure 1 is a bottom plan view of my improved dehydrator attachment mounted on a closure for a tank;

Fig. 2 is a vertical section taken on the line 2—2 of Fig. 1;

Fig. 3 is a fragmentary vertical section through a fuel tank filling pipe of common type and with the normal operating position of my device on the pipe indicated in broken lines, and

Fig. 4 is a side elevational view showing one of my improved containers for dehydrating material.

Referring to Fig. 2 of the drawing, granular dehydrating material 5 is shown as the filling in a substantially cylindrical container 6. This container is preferably constructed from a strong transparent plastic such as polystyrene, methyl-methacrylate or cellulose acetate butyrate. Silica gel is the best known dehydrating material 5 and this is impregnated with a coloring agent such as cobalt chloride which is subject to a change in color from blue to pink when the dehydrating material becomes saturated or when it has adsorbed a predetermined proportion of moisture. The container 6 is molded with an opening which may be closed by an end member 7 after being filled with the material 5, the joint being sealed by the

2

use of an adhesive or by fusing the member 7 to the container walls. Depending from the end member 7 is a multiplicity of vertically elongated tubes 8 each having a minute axial passage for placing the interior of the container in communication with the interior of the tank when in use. A reduced and threaded upper end portion 9 is formed on the container 6 for attachment to a tank member and an annular shoulder 10 at the base of the portion 9 supports a washer 10 for making a sealed connection with the tank member.

As shown in Figs. 1 and 2, the threaded end portion 9 of the container 6 fits in an internally threaded bearing 11 which is fixed concentrically in a circular closure cap indicated generally by the numeral 12 for the fuel tank. This cap is adapted to close the mouth of the pipe 13 (Fig. 3) which projects upward from the tank (not shown) and is ordinarily used for charging the tank with fuel. Details of the connection between the cap 12 and pipe 13 are old and well known. As shown, they include an annular flange 14 extending inward around the mouth of the pipe 13 and formed with notches 15 to receive lugs 16 projecting from an inverted cup-shaped member 17 of the cap. Spaced upward from the lugs 16 is a somewhat resilient metal disk 18 forming an annular bearing for a gasket 19, the lower face 30 of which is adapted to make contact with the flange 14 of the pipe 13. Mounted above the disk 18 within the cap is a dish-shaped member 20 having a peripheral flange engaging the inner periphery of a cap flange 12a. This member 20 is formed with a vent opening 21 for placing the space above it in communication with an annular space at the outer periphery of the gasket 19. A second vent passage 22 places the interior of the tank in communication with the space above the member 20 when the cap is in place on the tank.

To lock the cap 12 on the pipe 13, the lugs 16 are passed downward through the openings 15 and then the cap is turned approximately one-quarter of a revolution to move the lugs beneath inclined cam surfaces 23 which are formed on a pendant extension 24 of the flange 14, thus bringing the lugs 16 to a locking position such as that indicated in broken lines in Fig. 3. With the cap in place on the pipe 13 it will be evident that the tubular members 8 place the interior of the tank in communication with the interior of the receptacle 6 at an elevation substantially above the normal level of the liquid in the tank.

As the fuel or other liquid is withdrawn from the tank it is replaced by air entering beneath

the outer periphery of the cap 12 and passing through the vent opening 21 and passage 22 at one side of the container 6. Such moisture as may enter with the air through the vent passages as well as that otherwise admitted to the tank is quickly adsorbed by the dehydrating material 5 since this material has a strong affinity for moisture and draws it up through the tubes 8. These tubes perform the further function of excluding fuel from the container 6 when movement of the vehicle causes splashing of the fuel against the bottom of the container 6. It is desirable ordinarily to exclude the liquid fuel from the dehydrating material since if it is allowed to stand in contact with silica gel it causes some discoloration which might be confused with a change in color due to adsorption of moisture.

By exposing the upper end 6a of the transparent container 6 to view above the cap 12, I make it unnecessary to remove the cap for inspection of the condition of the dehydrating material. When this material becomes saturated, as indicated by a change in its color from blue to pink, the container 6 is merely detached by unscrewing the threaded end portion 8 from the cap and replacing the container 6 with a similar one containing regenerated or dried material. By the use of my device the air above the liquid in the tank may be kept sufficiently dry to eliminate danger of engine failures resulting from the freezing of condensed moisture during operation under low temperature conditions.

Having described my invention, what I claim as new and desire to protect by Letters Patent is:

1. In combination with a closure for closing a filling opening of a tank for liquid, a container for dehydrating material detachably mounted on said closure, at least a portion of said container being transparent, dehydrating material and a coloring agent in said container, said coloring agent being subject to change in color upon the absorption of a predetermined quantity of moisture by the dehydrating material, said container having openings formed in its bottom wall for communicating with the atmosphere in said tank

above the level of liquid therein and being subject to the splashing of the liquid in the tank under certain operating conditions and means projecting from and below said container for guarding against the splashing of the liquid on said dehydrating material therein.

2. In combination with a closure for closing a filling opening of a tank for liquid, a container for dehydrating material detachably mounted on said closure, at least a portion of said container being transparent, dehydrating material and a coloring agent in said container, said coloring agent being subject to change in color upon the absorption of a predetermined quantity of moisture by the dehydrating material, said container being subject to the splashing of the liquid in the tank under certain operating conditions and pendant, elongated tubes carried by said container and formed to place the interior of the container in communication with the interior of the tank for subjecting the atmosphere above the liquid in the tank to the dehydrating effect of said material and guarding against the exposure of said dehydrating material to the splashing of liquid from said tank when in motion.
